CAMPER

James M. Coates, 7141 Birdview Drive, Malibu, Calif.

Filed July 27, 1962, Ser. No. 71,071

Term of patent 14 years

(Cl. D14—3)

FIG. 1.

FIG. 2.

FIG. 3.

FIG. 4.

I claim:

The ornamental design for a camper, substantially as shown and described.
